CLAIM

The ornamental design for a worklight, as shown and described.

DESCRIPTION

FIG. 1 is a right side perspective view of the worklight design;

FIG. 2 is a bottom, rear, and left perspective view thereof;

FIG. 3 is a top view thereof;

FIG. 4 is a bottom view thereof;

FIG. 5 is a right side view thereof;

FIG. 6 is a left side view thereof, but with the worklight in a first alternate position;

FIG. 7 is a front view thereof, but with the worklight in the position of FIG. 1;

FIG. 8 is a rear view thereof;

FIG. 9 is a left side perspective view thereof, but with the worklight in the position of FIG. 6;

FIG. 10 is a right side perspective view thereof, but with the worklight in a second alternate position;

FIG. 11 is a bottom, rear, and right perspective view of the worklight thereof, but with the removable battery shown separately for clarity of illustration and with the worklight in the position of FIG. 6;

FIG. 12 is a rear perspective view of the worklight without the removable battery for clarity of illustration; and,

FIG. 13 is an enlarged perspective view of the removable battery and charging port thereof but shown in an open position and separately for clarity of illustration.

1 Claim, 9 Drawing Sheets
